US00D461447S

(12) **United States Design Patent** (10) Patent No.: **US D461,447 S**
 (45) Date of Patent: **** Aug. 13, 2002**

(54) BATTERY CHARGER	DE	037999	10/1996
(75) Inventor: Damon J. Nawrozki, Parkville, MD (US)	DE	039569	3/1997
(73) Assignee: Black & Decker Inc., Newark, DE (US)	DE	039571	3/1997
(73) Assignee: Black & Decker Inc., Newark, DE (US)	DE	042050	11/1997
(73) Assignee: Black & Decker Inc., Newark, DE (US)	DE	042051	11/1997
(**) Term: 14 Years	DE	042733	1/1998
(21) Appl. No.: 29/149,107	DE	044310	6/1998
(22) Filed: Oct. 3, 2001	DE	044513	7/1998
(51) LOC (7) Cl. 13-02	DE	047201	10/1998
(52) U.S. Cl. D13/107	DE	048719	8/1999
(58) Field of Search D13/107, 108; 320/107-115	DE	049625	10/1999
	DE	053595	10/2000

FIG. 1 is a front perspective view of a battery charger showing my design.
 FIG. 2 is a top plan view thereof.

FIG. 3 is a bottom plan view thereof.

FIG. 4 is a right side elevational view thereof.

FIG. 5 is a left side elevational view thereof.

FIG. 6 is a front elevational view thereof; and,

FIG. 7 is a rear elevational view thereof.
